FOOD PACKAGE

Gino Prestigiacomo, 5116 N. Mango Ave., Chicago 30, Ill.

Filed Mar. 13, 1964, Ser. No. 78,995

Term of patent 14 years

(Cl. D58—11)

FIG. 1 is a top plan view of a food package, showing my new design;

FIG. 2 is an elevational view of one side thereof, the other side view being the same;

FIG. 3 is a bottom plan view thereof;

FIG. 4 is an elevational view of the front thereof; and

FIG. 5 is an elevational view of the rear thereof.

I claim:

The ornamental design for a food package, substantially as shown, and described.
